GOLF CLUB

Richard Martinez, 6111 Gotham St., Bell Gardens, Calif.

Filed Nov. 16, 1964, Ser. No. 82,637

Term of patent 14 years

(Cl. D34—5)

FIG. 1 is a perspective view of a golf club showing my new design;

FIG. 2 is a side elevational view, as seen from the right side in FIG. 1;

FIG. 3 is a rear elevational view;

FIG. 4 is a slightly enlarged plan view; and

FIG. 5 is a similarly enlarged bottom plan view of the same.

I claim:

The ornamental design for a golf club, substantially as shown.
